UNITED STATES PATENT OFFICE.

FREDERICK WILLIAM ANDREW, OF BROOKLYN, NEW YORK, ASSIGNOR TO EISEMANN MAGNETO CORPORATION, OF BROOKLYN, NEW YORK, A CORPORATION OF NEW YORK.

MAGNETO FOR GAS-ENGINES.

1,374,542.

Specification of Letters Patent. Patented Apr. 12, 1921.

Application filed June 28, 1920. Serial No. 391,133.

To all whom it may concern:

Be it known that I, FREDERICK WILLIAM ANDREW, a citizen of the United States, and a resident of the city of New York, borough 5 of Brooklyn, county of Kings, and State of New York, have invented certain new and useful Improvements in Magnetos for Gas-Engines, of which the following is a full, clear, and exact specification.

10 My invention relates to magnetos used for igniting the explosive mixtures in gas engines, and its object is to provide an electric ignition machine in which the impulse starter and the adjustable driving connection therefor are inclosed in a casing or cover secured to the magneto frame.

It is well known that in magneto installations for gas engines, the impulse starter must be driven by the engine shaft through 20 a flexible or automatically adjustable connection, so as to avoid binding and prevent the nonfunctioning of the magneto. In the prior constructions, this flexible or adjustable connection was in part attached to the 25 impulse starter mounted on the magneto shaft and in part to the engine-driven shaft mounted separately from the magneto. Furthermore, the impulse starter and its flexible coupling, being thus separately 30 mounted, were left exposed. Now, when an auto-vehicle is operated for long periods of time over dusty ground (as, for instance, a tractor used in dusty fields), the abrasive character of the dust has a deleterious effect 35 on the exposed impulse starter and its flexible coupling, causing the parts to wear out prematurely.

To remedy the foregoing defects and disadvantages, I have devised a magneto in 40 which the impulse starter and the flexible coupling are inclosed in a substantially dust-proof casing or cover carried by the magneto frame. In this new construction, the magneto carries not only the impulse starter, 45 but the flexible coupling as well; so that it is only necessary to have an ordinary type of connection between the engine and the driving shaft of the impulse starter.

One embodiment of my invention is illus- 50 trated in the accompanying drawings, in which—

Figure 1 shows a portion of a magneto containing a preferred form of my invention;

55 Fig. 2 is an enlarged view similar to Fig.

1, the casing or cover containing the impulse starter and the flexible coupling being shown in longitudinal cross-section to expose the parts within;

Fig. 3 is an end view of the magneto 60 shown in Fig. 1, with the casing or cover removed;

Fig. 4 is a detached front view of the casing or cover which incloses the impulse 65 starter and the flexible coupling; and

Fig. 5 is a perspective view of the coupling disk between the impulse starter and its driving shaft.

As my invention may be applied to various types and forms of magnetos, I have 70 not deemed it necessary to illustrate any particular magneto construction, and so I have merely shown a portion of the supporting framework 1 which carries the permanent field magnets 2 and the other usual 75 parts appertaining to machines of this type. The framework has an end plate 3 in which is journaled one end of the rotatable magneto shaft 4. On the projecting end of the magneto shaft 4 is mounted an impulse 80 starter, indicated as a whole by IS. The specific form of impulse starter is not material to my invention, and for the sake of convenience I have shown an impulse 85 starter like that disclosed in my Patent No. 1,342,199, dated June 1, 1920. It will, therefore, not be necessary to describe here the details of construction and operation of this impulse starter, for these are set forth in my aforesaid patent. For the purpose of 90 explaining my present invention, it is sufficient to say that the impulse starter IS comprises the driving member 5 and the driven member 6, which are operatively connected together by the coil spring 7. The driving member 5 is provided with diametrically arranged lugs 8 for engaging in the notches 9 of the coupling disk 10.

The impulse starter is inclosed in a substantially dust-proof casing or cover, indicated as a whole by C. This casing or cover is secured to the framework of the magneto. In the drawing I have shown the casing C secured to the end plate 3 by means of screws 11, which pass through the openings 100 12 of the casing into the screw-threaded holes 13 of the end plate. Other suitable ways and means may be employed for attaching the casing C to the magneto frame.

Preferably the axial alignment of the 110

shafts 4 and 16 is facilitated and maintained by establishing a centering and locking connection between the casing C and the magneto frame. In the particular construction shown in the drawings, I secure this connection by providing the casing with a circumferential shoulder *a* adapted to fit over and interlock with the circumferential shoulder *b* on the end plate 3. This connection insures the necessary alinement of the shafts 4 and 16, and at the same time holds the casing rigidly on the magneto frame. Other centering and locking means may be employed for the casing C.

The end wall 14 of the casing or cover C is provided with a bearing 15, in which is journaled the stub-shaft 16. The bearing 15 may be of any suitable construction, plain or ball-bearing. As seen from Fig. 2, the magneto shaft 4 and the stub-shaft 16 are substantially in axial alinement. The outer or exposed end of the stub-shaft is adapted to be operatively connected with the engine shaft by means of any suitable coupling or connection, which it is not necessary to describe or illustrate. The inner end of the stub-shaft 16 is provided with a disk 20 having a pair of diametrically opposite lugs 21 arranged to engage in the notches or recesses 22 of the coupling disk 10.

The coupling thus formed between the driving member 5 of the impulse starter (or, more broadly speaking, between the magneto shaft) and the driving stub-shaft 16 is flexible or automatically adjustable, and allows for the eccentric play of the magneto shaft 4 and the stub-shaft 16. In the broader aspect of my invention, the particular type of automatically adjustable coupling between the impulse starter and its driving shaft 16 is immaterial. I have shown the Oldham type of coupling, because that is the one I have used in practice and found satisfactory. When I speak here of a "flexible" coupling, I mean one that is automatically adjustable during the operation of the machine and will allow for such eccentric displacement of the magneto shaft and the driving shaft for the impulse starter as is bound to occur in practice. The diametrically opposite notches 9 and 22 of the coupling disk 10, being arranged at right angles, render the coupling flexible or adjustable, as will be readily understood.

It will be seen from the foregoing that the casing or cover C, which I prefer to have as dust-proof as possible, incloses not only the impulse starter, but also the flexible coupling for driving the same. By making this flexible driving coupling a part of the magneto unit, it is necessary to use only an ordinary form of coupling to connect the shaft 16 to the engine. This

greatly facilitates the proper installation of the magneto on the engine. The cover C protects the inclosed parts from dust and other deleterious elements.

Attention is also called to the fact that the casing or cover C is removable without separating the members of the impulse starter. When the casing is removed, the impulse starter is fully exposed for inspection and repair. The universal coupling between the magneto shaft 4 and the stub-shaft 16 automatically separates when the cover is pulled off and easily (almost automatically) goes together when the cover is put on. This ready (I might say automatic) coupling and uncoupling of the two shafts 4 and 16 by merely positioning and removing the cover C is a decided advantage not found in prior structures, as far as I am aware.

While I have herein shown and described a specific form of structure embodying my invention, I want to make it clear that I have done so merely for the sake of illustration and that I am not to be limited to the details set forth. Changes and modifications will, undoubtedly, occur to those skilled in the art and still be within the bounds of my invention as defined in the appended claims.

I might add, to prevent any possible misunderstanding, that I use the term "gas engine" in the specification and claims in the ordinary present-day acceptation—namely, any internal combustion engine.

I claim as my invention:

1. In a magneto for gas engines, a framework through which projects one end of the magneto shaft, an impulse starter operatively mounted on said projecting end of the shaft, said impulse starter comprising a driven member and a driving member, a casing or cover secured to said framework and inclosing said impulse starter, a stub-shaft journaled in said casing in axial alinement with the magneto shaft and projecting outside the casing for connection with the engine, said casing and stub-shaft being removable and replaceable as a unit without disturbing said members of the impulse starter, and automatically adjustable coupling means within said casing for connecting the driving member of the impulse starter to said stub-shaft, said coupling means comprising readily separable and unitable parts which permits ready removal and replacing of the casing and stub-shaft.

2. In a magneto for gas engines, a framework through which projects one end of the magneto shaft, an impulse starter operatively mounted on said projecting end of the shaft, said impulse starter comprising a driven member and a driving member, lugs on said driving member, a casing or cover

secured to said framework and inclosing said impulse starter, a stub-shaft journaled in said casing in axial alinement with the magneto shaft and projecting outside the casing for connection with the engine, said casing and stub-shaft being removable and replaceable as a unit without disturbing said members of the impulse starter, the inner end of said stub-shaft being provided with 5 lugs, and a coupling disk positioned between the driving member of the impulse starter and the inner end on the stub-shaft, said coupling disk having notches or recesses for engaging both sets of said lugs, 10 said coupling disk and lugs permitting ready removal and replacing of the casing and stub-shaft.

3. In a magneto for gas engines, a framework having a closed casing or cover secured at one end thereof, an impulse starter mounted on the magneto shaft within said casing, a driving stub-shaft journaled in said casing and having a portion projecting outside for connection with the engine, said 20 casing and stub-shaft being removable and replaceable as a unit without disturbing said members of the impulse starter, and a flexible or adjustable coupling within said casing for operatively connecting the impulse 25 starter to said stub-shaft, said coupling being automatically separable when the casing and stub-shaft are removed.

4. In a magneto for gas engines, a framework through one end of which projects the magneto shaft, a casing removably secured to said end of the framework, a stub-shaft journaled in said casing in axial alinement with the magneto shaft and projecting beyond the casing for connection with the engine, an impulse starter within said casing, 35 said impulse starter comprising a driving member and a driven member arranged between said magneto shaft and said stub-shaft, and a coupling within said casing for transmitting the rotation of said engine-driven stub-shaft to said magneto shaft through said impulse starter, said coupling being automatically separable when said casing and stub-shaft are removed, said casing 40 and stub-shaft being removable from and replaceable on said framework without separating the members of said impulse starter.

5. In a magneto for gas engines, a framework including an end plate provided with a bearing for the magneto shaft which projects through said end plate, an impulse starter comprising a driven member and a driving member, a casing or cover secured 50 to said end plate and inclosing said impulse starter, a stub-shaft journaled in the outer

end of said casing in axial alinement with the magneto shaft and projecting outside the casing for connection with the engine, said casing and stub-shaft being removable 65 and replaceable without separating said members of the impulse starter, and a lug-and-slot driving connection between said magneto shaft and said stub-shaft for transmitting the rotation of the stub-shaft to the 70 magneto shaft through the impulse starter, said lug-and-slot connection being automatically separable when the casing and stub-shaft are removed.

6. In a magneto for gas engines, a framework including an end plate provided with a bearing for the magneto shaft which projects through said end plate, an impulse starter comprising a driven member and a driving member, a casing or cover secured 75 to said end plate and inclosing said impulse starter, a stub-shaft journaled in the outer end of said casing in axial alinement with the magneto shaft and projecting outside the casing for connection with the engine, 80 said casing and stub-shaft being removable and replaceable without separating said members of the impulse starter, an automatically adjustable coupling within said casing for transmitting the rotation of the 85 stub-shaft to the magneto shaft through the impulse starter, said coupling being automatically separable when the casing and stub-shaft are removed, and interlocking means on said end plate and said casing for 90 centering the casing on the end plate and maintaining it in that position.

7. In a magneto for gas engines, a substantially dust-proof casing or cover removably secured to one end of the magneto 100 frame, an impulse starter within said cover, a driving shaft journaled in said cover and adapted to be connected with the engine, and an automatically adjustable coupling within said casing for transmitting the rotation of 105 said driving shaft to the magneto shaft through said impulse starter, said coupling being automatically separable when the casing and driving shaft are removed.

8. In a magneto for gas engines, a substantially dust-proof casing or cover removably secured to one end of the magneto frame, an impulse starter within said cover, a driving shaft journaled in said cover and adapted to be connected with the engine, 110 and a lug-and-slot coupling within said casing for transmitting the rotation of said driving shaft to the magneto shaft through said impulse starter, said coupling being automatically separable when the casing 115 and driving shaft are removed.

FREDERICK WILLIAM ANDREW.
